UNITED STATES PATENT OFFICE.

FRANCIS H. RICHARDS, OF HARTFORD, CONNECTICUT, ASSIGNOR, BY
MESNE ASSIGNMENTS, TO AMERICAN TYPOGRAPHIC CORPORA-
TION, A CORPORATION OF NEW JERSEY.

WHEEL-MOUNTING.

No. 837,963.

Specification of Letters Patent.

Patented Dec. 11, 1906.

Application filed January 2, 1901. Renewed March 16, 1905. Serial No. 250,407.

To all whom it may concern:

Be it known that I, FRANCIS H. RICHARDS, a citizen of the United States, residing at Hartford, in the county of Hartford and State of Connecticut, have invented certain new and useful Improvements in Wheel-Mountings, of which the following is a specification.

This invention relates to improvements in wheel-mountings, and more particularly to the provision of means for so attaching closely-contiguous die wheels or carriers of typographic machines to the concentric shafts upon which they are mounted side by side that any one may be readily removed without disturbing the companion wheels. Thereby also carriers of equal thickness with the impression devices mounted on each, respectively, may be operated in close contiguity when mounted concentrically.

In the accompanying drawings, Figure 1 is a side elevation of a set of shafts with carriers thereon, a portion of the dies being shown in place. Fig. 2 is an end elevation thereof looking from the left with all the dies in place. Fig. 3 is a longitudinal section on the line *a a* of Fig. 2. Fig. 4 is a top plan view of Fig. 1. Fig. 5 is an end elevation of one of the carriers. Fig. 6 is a similar view of the head on the shaft for receiving the same. Fig. 7 is a detail showing the screws for securing these parts together. Fig. 8 is a perspective view of the inner shaft and its head. Fig. 9 is a similar view of one of the outer concentric shafts. Fig. 10 is a side elevation of Fig. 5 looking from the right, and Fig. 11 is a central longitudinal horizontal section through Fig. 1.

Similar characters designate like parts throughout the different figures of the drawings.

A set of shafts *S*, here shown as three in number, are concentrically arranged, the inner one, 11, being preferably solid and the outer ones, 12, tubular. Transversely mounted at one end of each of the shafts 11 and 12 is a plate forming a head 13, perimetrical rectangular in form, except that two corners thereof are rounded. Each head 13 rotates with its respective shaft and is located transversely concentric with, but longitudinally eccentric thereto. Mounted on each head 13, respectively, is a carrier 14, preferably of

equal thickness with the former and recessed, as at 13', to fit thereon. The carrier when mounted as aforesaid is concentric with its shaft. Suitable engagement of each carrier 14 with its head 13 is provided to prevent transverse motion of the former relative to the latter. In the form shown herein tongues 18 18 and grooved edges 19 19 are provided for this purpose. Means (shown herein as headed screws 22 22) are provided to engage with each carrier 14 and its respective head 13 and retain the former in place on the latter. Impression devices 16 16 or any desired elements properly operative in combination with those shown and described may be mounted upon the peripheries of the carriers 14 14 and retained thereon by engagement therewith in any suitable manner.

In use the wheels above described will usually be situated closely side by side upon their respective shafts, and if for any reason it is desired to remove one of them the screws 22 are taken from the desired wheel, when it may then be slid laterally from its head without disturbing any of the others and as readily replaced.

While this mounting is particularly applicable to the die-wheels of typographic machines, in connection with which it has been described, it is evident that it might be equally well used in many other connections.

If it is merely desired to remove one or more dies from one of the wheels, the wheel may be turned until the die in question lies between the unoccupied spaces of the adjacent wheels, when it becomes readily accessible.

Having thus described my invention, I claim--

1. The combination with a member, of a head supported thereby and a pair of whose opposite edges constitute guide-faces extending transversely to the axis of said member and from one side of said axis to at least the points of intersection of said guide-faces with a line which passes through said axis perpendicularly to said guide-faces; and a detachable carrier having a recess whose side walls engage with said guide-faces and which recess extends inward from one edge of the carrier and opens through one side across the opposite side face thereof.

2. The combination with a member, of a

head supported thereby and a pair of whose opposite edges constitute parallel guide-faces extending transversely to the axis of said member and from one side of said axis to 5 beyond the points of intersection of said guide-faces with a line which passes through said axis perpendicularly to said guide-faces; and a detachable carrier having a recess whose side walls engage with said guide-faces and which recess extends inward from one edge 70 of the carrier and opens through one side across the opposite side face thereof; and connecting-screws extending through openings in the head and engaging with the bottom wall of the recess in the carrier.

3. The combination with a member, of a head supported thereby and a pair of whose opposite edges constitute guide-faces extending transversely to the axis of said member and from one side of said axis to at least the points of intersection of said guide-faces 15 with a line which passes through said axis perpendicularly to said guide-faces; a detachable carrier having a recess whose side walls engage with said guide-faces and which recess extends inward from one edge of the carrier and opens through one side across the 20 opposite side face thereof; and means for fixedly attaching said carrier to said head.

4. The combination with a member, of a head supported thereby and a pair of whose opposite edges constitute guide-faces extending transversely to the axis of said member and from one side of said axis to at least the points of intersection of said guide-faces 25 with a line which passes through said axis perpendicularly to said guide-faces; a detachable carrier having a recess whose side walls engage with said guide-faces and which recess extends inward from one edge of the carrier and opens through one side across the 30 opposite side face thereof; and connecting-pins extending through openings in the head and engaging with the bottom wall of the recess in the carrier.

5. The combination with a member, of a head supported thereby and a pair of whose opposite edges constitute guide-faces extending transversely to the axis of said member and from one side of said axis to at least the points of intersection of said guide-faces 35 with a line which passes through said axis perpendicularly to said guide-faces; a detachable carrier having a recess whose side walls engage with said guide-faces and which recess extends inward from one edge of the carrier and opens through one side across the 40 opposite side face thereof; and connecting-pins extending through openings in the head and engaging with the bottom wall of the recess in the carrier.

6. The combination with a member, of a head supported thereby and a pair of whose opposite edges constitute parallel guide-faces extending transversely to the axis of said member and from one side of said axis 45 to beyond the points of intersection of said

guide-faces with a line which passes through said axis perpendicularly to said guide-faces; a detachable carrier having a recess whose side walls engage with said guide-faces and which recess extends inward from one edge 70 of the carrier and opens through one side across the opposite side face thereof; and connecting-screws extending through openings in the head and engaging with the bottom wall of the recess in the carrier.

7. The combination with a shaft, of a head supported thereby and a pair of whose opposite edges constitute guide-faces extending transversely to the axis of said member and from one side of said axis to at least the 80 points of intersection of said guide-faces with a line which passes through said axis perpendicularly to said guide-faces; and a detachable carrier having a recess whose side walls engage with said guide-faces and which recess extends inward from one edge of the carrier and opens through one side across the 85 opposite side face thereof.

8. The combination with a shaft, of a head supported thereby and a pair of whose opposite edges constitute parallel guide-faces extending transversely to the axis of said member and from one side of said axis to beyond the points of intersection of said guide-faces 90 with a line which passes through said axis perpendicularly to said guide-faces; and a detachable carrier having a recess whose side walls engage with said guide-faces and which recess extends inward from one edge of the carrier and opens through one side across the 95 opposite side face thereof.

9. The combination with a shaft, of a head supported thereby and a pair of whose opposite edges constitute guide-faces extending transversely to the axis of said member and from one side of said axis to at least the points of intersection of said guide-faces with a line 100 which passes through said axis perpendicularly to said guide-faces; a detachable carrier having a recess whose side walls engage with said guide-faces and which recess extends inward from one edge of the carrier and opens through one side across the opposite side face thereof; and connecting-screws extending 105 through openings in the head and engaging with the bottom wall of the recess in the carrier.

10. The combination with a shaft, of a head supported thereby and a pair of whose opposite edges constitute guide-faces extending transversely to the axis of said member and from one side of said axis to at least the points of intersection of said guide-faces with a line which passes through said axis perpendicularly to said guide-faces; a detachable 110 carrier having a recess whose side walls engage with said guide-faces and which recess extends inward from one edge of the carrier and opens through one side across the opposite side face thereof; and connecting-screws 115 extending through openings in the head and engaging with the bottom wall of the recess in the carrier.

extending through openings in the head and engaging with the bottom wall of the recess in the carrier.

11. The combination with a member, of a head supported thereby and a pair of whose opposite edges constitute channeled guide-faces extending transversely to the axis of said member and from one side of said axis to at least the points of intersection of said guide-faces with a line which passes through said axis perpendicularly to said guide-faces, and a detachable carrier having a recess whose side walls engage with said guide-faces and which recess extends inward from one edge of the carrier and opens through one side across the opposite side face thereof.
12. The combination with a member, of a head supported thereby and a pair of whose opposite edges constitute parallel channeled guide-faces extending transversely to the axis of said member and from one side of said axis to beyond the points of intersection of said guide-faces with a line which passes through said axis perpendicularly to said guide-faces; and a detachable carrier having a recess whose side walls engage with said guide-faces and which recess extends inward from one edge of the carrier and opens through one side across the opposite side face thereof.

13. The combination with concentric shafts, of a head supported by each such shaft and a pair of whose opposite edges constitute guide-faces extending transversely to the axis of said concentric shafts and from one side of said axis to at least the points of intersection of said guide-faces with a line which passes through said axis perpendicularly to said guide-faces; and a detachable carrier having a recess whose side walls engage with said guide-faces and which recess extends inward from one edge of the carrier and opens through one side across the opposite side face thereof.

14. The combination with concentric shafts, of a head supported by each such shaft and a pair of whose opposite edges constitute parallel guide-faces extending transversely to the axis of said member and from one side of said axis to beyond the points of intersection of said guide-faces with a line which passes through said axis perpendicularly to said guide-faces; and a detachable carrier having a recess whose side walls engage with said guide-faces and which recess extends inward from one edge of the carrier and opens through one side across the opposite side face thereof.

15. The combination with concentric shafts, of a head supported by each such shaft and a pair of whose opposite edges constitute guide-faces extending transversely to the axis of said concentric shafts and from one side of said axis to at least the points of intersection of said guide-faces with a line which passes through said axis perpendicularly to said guide-faces; and a detachable carrier having a re-

cess whose side walls engage with said guide-faces and which recess extends inward from one edge of the carrier and opens through one side across the opposite side face thereof; and connecting-screws extending through openings in the head and engaging with the bottom wall of the recess in the carrier.

16. The combination with concentric shafts, of a head supported by each such shaft and a pair of whose opposite edges constitute guide-faces extending transversely to the axis of said concentric shafts and from one side of said axis to at least the points of intersection of said guide-faces with a line which passes through said axis perpendicularly to said guide-faces; a detachable impression-device carrier for each head having a recess whose side walls engage with the guide-faces of the head and which recess extends inward from one edge of the carrier and opens through one side across the opposite side face thereof; and a plurality of impression devices supported on each carrier.

17. The combination with concentric shafts, of a head supported by each such shaft and a pair of whose opposite edges constitute parallel guide-faces extending transversely to the axis of said member and from one side of said axis to beyond the points of intersection of said guide-faces with a line which passes through said axis perpendicularly to said guide-faces; a detachable impression-device carrier for each head having a recess whose side walls engage with the guide-faces of the head and which recess extends inward from one edge of the carrier and opens through one side across the opposite side face thereof; and a plurality of impression devices supported on each carrier.

18. The combination with concentric shafts, of a head supported by each such shaft and a pair of whose opposite edges constitute parallel guide-faces extending transversely to the axis of said member and from one side of said axis to beyond the points of intersection of said guide-faces with a line which passes through said axis perpendicularly to said guide-faces; a detachable impression-device carrier for each head having a recess whose side walls engage with the guide-faces of the head and which recess extends inward from one edge of the carrier and opens through one side across the opposite side face thereof; a plurality of impression devices supported on each said carrier; and connecting-screws extending through openings in each head and engaging with the bottom wall of the recess in the carrier associated with the head.

19. The combination with a member, of a head supported thereby and certain faces of which constitute guides extending transversely to the axis of said member, and from one side of said axis to at least the points of intersection of said guide-faces with a line which passes said axis relatively transverse

- to said guide-faces, and a detachable carrier having a recess whose side walls engage with said faces, which recess extends inward from one edge of the carrier and opens through one side across the opposite side face thereof.
20. A plurality of closely-contiguous parallel series of impression devices, each series separably mounted on the periphery of a carrier, said carriers having a series of concentric shafts severally operatively engaging said carrier, and means located within the extreme radial faces of said carriers for severally disengaging each carrier from its respective shaft.
21. A plurality of heads perimetrically rectangular in form respectively mounted upon and rotated by concentric shafts, a plurality of members each carrying a plurality of impression devices and having recesses mating with and mounted upon said heads.
22. A plurality of closely-contiguous parallel series of impression devices, each series severally mounted on a carrier, said carriers, a series of concentric shafts having perimet- 25 rically rectangular heads severally operatively engaging similarly-formed recesses in said carriers, and means located within the extreme radial faces of said carriers for severally disengaging each carrier from its respective shaft.
23. A plurality of closely-contiguous parallel series of impression devices, each series severally mounted on a carrier, said carriers, a series of concentric shafts severally operatively engaging said carriers by means of plates and recesses perimetrically rectangular, and means for detachably securing each carrier upon its respective shaft.
24. A plurality of series of impression devices, each series severally mounted upon a rotatably-mounted carrier, said carriers arranged in close assemblage, a series of independent shafts severally operatively engaging said carriers, and means for severally disengaging each carrier from its respective shaft while the same are closely assembled.
25. A plurality of closely-contiguous parallel series of impression devices, each series severally mounted on a revolving carrier, 45 said revolving carriers being mounted upon a series of independently-operable shafts severally being in the form of plates and engaging said carriers and located within the extreme radial faces of said carrier, and bolts for con-necting and for disengaging said carrier from its respective shaft-plate.
26. The combination with a rotatably-mounted head, of a number of independent series of impression devices carried thereby, said head being divided into independent 60 members for carrying and for operating each said series, and means for independently rotating each member of the head.
27. The combination with a rotatably-mounted head, of a number of independent 65 series of impression devices carried thereby, said head being divided into independent members for carrying and for operating each said series, means for independently rotating each member of the head, and means for removing each of said members individually.
28. The combination, with a number of concentrically-disposed shafts, each provided with a head, of a wheel carried by each shaft and provided with a lateral opening for receiving said head, and guides upon the head and wheel for co-operative engagement for assuring a constant longitudinal position on the shaft.
29. The combination with a shaft provided 80 with a head, of a wheel carried by the shaft provided with a lateral opening for receiving said head and having engagement therewith to assure positive position longitudinally of the shaft, and transversely-disposed fastening means.
30. The combination with a wheel provided with impression devices and carried by a shaft, said wheel being provided with a lateral opening for receiving a head on the shaft 90 and having engagement therewith to assure positive position longitudinally of the shaft, and screw-bolts transversely disposed for fastening said head and carrier together.
31. The combination with a plurality of 95 carriers, each having impression devices upon its perimeter, of heads for carrying said carriers in close assemblage and each fast upon a shaft, the heads and carriers having mating guides for permitting disassembly by movement radially of the shaft, and disengageable means for preventing radial movement.

FRANCIS H. RICHARDS.
